FLEXIBLE POURING SPOUT FOR A CONTAINER

Leon D. Grebow, New York, N.Y.
(3850 Hudson Manor Terrace, Bronx, N.Y. 14716)

Filed Dec. 19, 1966, Ser. No. 5,117

Term of patent 14 years

(Cl. D58—26)

Fig. 2

Fig. 1

Fig. 3

FIG. 1 is an elevational view of a flexible pouring spout for a container embodying my new design, the opposite side being the same in appearance as the side shown.

FIGURE 2 is a top plan view.

FIGURE 3 is a bottom plan view.

I claim:

The ornamental design for a flexible pouring spout for a container, substantially as shown and described.
